Primary Examiner — Susan Bennett Hattan*Assistant Examiner* — Janice Hallmark(74) Attorney, Agent, or Firm — Pryor Cashman LLP; Andrew S. Langsam, Esq.(57) CLAIM

The ornamental design for a vaporization apparatus, as shown and described.

DESCRIPTION

FIG. 1 is a front view of a vaporization apparatus showing my new design;

FIG. 2 is a rear view thereof;

FIG. 3 is a left side view thereof;

FIG. 4 is a right side view thereof;

FIG. 5 is a top view thereof; and,

FIG. 6 is a bottom view thereof.

In the drawings, the dot-dot-dash broken lines depict the bounds of the claimed design and the dash-dash broken lines depict parts of the vaporization apparatus; All broken lines form no part of the claimed design.
